UNITED STATES PATENT OFFICE.

JOSÉ M. URBIETA, OF SAN ANTONIO, TEXAS.

JOURNAL-LUBRICATOR.

1,293,254.

Specification of Letters Patent. Patented Feb. 4, 1919.

Application filed September 17, 1917. Serial No. 191,834.

To all whom it may concern:

Be it known that I, JOSÉ M. URBIETA, a citizen of Mexico, residing at San Antonio, in the county of Bexar and State of Texas, have invented certain new and useful Improvements in Journal-Lubricators, of which the following is a specification.

This invention has relation to railway journal lubricators, and has for an object 10 to provide an improved device for this purpose embodying many novel and practical features of construction.

Another object of the invention is to provide a railway journal lubricator embodying a pair of rollers of a novel construction held in a manner to engage the journal to continuously supply lubricant thereto during rotation of the journal.

Another object of the invention is to provide a journal lubricator including a reservoir and parts appurtenant thereto adapted to engage snugly the journal thereby preventing waste of oil by insuring its return to the reservoir after contact with the journal.

A still further object of the invention is to provide shields in a railway journal lubricator of the character above described whereby to collect oil from the journal and return the same to the reservoir thereby preventing waste of oil.

A still further object of the invention is to provide a new and novel means for resiliently supporting the reservoir, and resilient means for supporting the lubricating rollers in contact with the journal thereby allowing for inequalities in the journals or bearings of the journal with the result that the journal is continuously and efficiently lubricated at all times.

A still further object of the invention is to provide a tool of a specific construction whereby my improved journal lubricator may be assembled within a journal box.

In addition to the foregoing my invention comprehends improvements in the details of construction and arrangement of the parts to be hereinafter more fully described and particularly set forth in the appended claims.

In the accompanying drawings in which similar and corresponding parts are designated by the same characters of reference throughout the several views in which they appear:

Figure 1, is a view in side elevation of a conventional type of journal and journal box illustrating the embodiment therein of my invention, with parts of the journal box broken away to show the interior. 60

Fig. 2, is a view in perspective of the parts in assembled relation of my journal lubricator.

Fig. 3, is a view of the lubricator in plan.

Fig. 4, is a transverse section taken 65 through the lubricator on the line 4—4 of Fig. 2.

Fig. 5, is a longitudinal section taken through the lubricator.

Fig. 6, is a transverse sectional view of one 70 of the lubricator shields.

Fig. 7, is a view in perspective of the device for resiliently supporting the lubricator.

Fig. 8, is a view in side elevation of one of 75 the lubricating rollers.

Fig. 9, is a view in side elevation of a different form of lubricating roller, and

Fig. 10, is a view in perspective of the tool or device used for assembling the parts of my lubricator in a journal box. 80

With reference to the drawings 10 indicates a casing or journal box, 11 the journal, which is formed in the usual manner on its outer end with an annular enlargement 12, and 13 indicates the brasses or bearings located at the upper end of the journal box and against which the journal bears. 85

My improved journal lubricator comprises a reservoir proper 14 which is substantially rectangular in configuration and has opposite longitudinal sides rounded adjacent the bottom as at 15, the ends 16 of the reservoir being provided upon their upper edges with circular cut-away portions 17 to conform to the transverse curvature of the journals. 95 The under side of the reservoir, exteriorly thereof is formed with a pair of spaced longitudinally extending ribs 18 connected across their ends at the forward end of the reservoir by means of a transversely extending rib 19, a second rib 20 being disposed parallel to the rib 19 in spaced relation thereto to form a recess 21. The opposite end of the longitudinally extending ribs 18 are likewise connected by means of an integrally formed 100 plate 22 which extends from the rear end of the reservoir to a distance slightly inward from the rear end of the reservoir to form a recess 23. The forward end of the reservoir 105 is formed with a conduit 24 extending horizontally 110

zontally, the forward end of said conduit opening up into a funnel 25 whereby lubricant may be poured thereinto for filling the reservoir. It is to be further noted that the upper edges of the sides and ends of the reservoir are rabbeted or recessed as at 26.

A rectangular frame indicated at 27 is next provided and superposed upon the reservoir, the edges of the frame seated in the recess at rabbeted sides of the reservoir being shown clearly in Fig. 5. The ends 38 of said frame 27 are furthermore formed upon their upper edges with curved cut away portions 29 which coincide with the curved cut away portion 17 of the ends of the reservoir whereby to snugly fit and engage the journal. The ends 28 of the rectangular frame 27 are provided upon their inner sides adjacent the lower edges thereof with inwardly extending lugs 30 apertured to receive rivets 31 which also penetrate and serve to secure to the lugs a pair of spring strips 32 having their ends curved upwardly as at 33. The frame 27 is provided at each longitudinal edge with an integrally formed longitudinally extending strip 34 which are inclined in opposite directions with their lower edges in spaced relation to the inner surfaces of the longitudinal side members of said frame 27 as clearly shown in Fig. 4.

A pair of shields, one of which is shown in Fig. 3 are provided, formed of sheet metal if desired and comprising a transversely curved portion 35 formed upon one longitudinal edge with an edge 36 which are bent at right angles as at 37 at the ends of the shields and formed integrally with end portions 38 of the shield whereby said edges 36 and 37 may be seated within the upper side of the rectangular frame 27 as shown in Fig. 4. It will be noted that the shields 35 extend upwardly from the frame 27 at opposite sides of the journal to a distance adjacent the top of the journal adjacent the bearings 13. The upper longitudinal edges of the shields 35 may be cut away as at 39 to engage around the bearings 13 to more efficiently inclose the journal to prevent splashing of oil.

In use, the reservoir is inserted in a journal box, and beneath the journal, and supported upon a resilient device shown in detail in Fig. 7. This device comprises a pair of curved strips 40 and 41 of different lengths placed in contact and held together by means of a clip 42 which embraces both strips. One end of the strip 41 is formed with a bend as at 43, forming an edge which is designed to be seated within the recess 21 at the under side of the reservoir adjacent the forward end thereof as shown in Fig. 1 and a second bend 44 forming a finger engaging lip whereby the strip may be disengaged from said recess when desired. The outer end of the strip 41 is bent as at 45 and

the terminal of the strip is adapted to be inserted in the recess 23 formed by means of the plate 22 which spans the ends of the strips 18 at the rear end of the reservoir as shown.

Prior to inserting the reservoir within the journal a pair of rollers, different designs being shown in Figs. 1, 8 and 9, are supported in the reservoir, each roller having journals 46 on their ends which are supported in the curved ends 33 of the springs 32 which in turn are supported from the lugs within the rectangular frame 27. The frame 27 may be inserted in the journal box after the reservoir is placed therein and after the rollers are supported within the said frame. To this end, I provide a trunnion 47 on the longitudinal sides of the frame 27 exteriorly thereof, and I provide a tool shown in Fig. 10 which comprises a pair of strips 48 connected together as at 49 to form a handle, the opposite ends of the strips being cut away as at 50 to receive the trunnion 47 whereby the rectangular frame 27 may be supported within the tool. Prior to the insertion of the rectangular frame 27 within the journal box, the shields shown in Fig. 6 are supported upon the longitudinal edges of the frame, as shown in Fig. 2. These shields then engage around the journal at opposite sides and extend upwardly and around the brasses 15.

From the foregoing it will be apparent that the reservoir is resiliently supported upon the device shown in detail in Fig. 7 and the rollers indicated generally as 51 are resiliently held by means of the spring strips 32 against the journal, at the same time permitting rotation of the rollers during rotation of the journal by frictional contact therebetween. It will also be apparent that the journal is engaged by the ends of the reservoir and also the ends of the rectangular frame 27, thereby confining the lubricant within a certain area to prevent splashing and consequent waste thereof. During rotation of the journal the lubricant is carried upward, being applied thereto by means of a roller 51, and any lubricant which may be splashed from the journal is caught by means of the shield 35 and directed downwardly flowing into the reservoir. It will be noted that the strips 35 which are in the frame 27 serve to deflect the lubricant as it is received from the shield and also from the journal to guide the same back into the reservoir.

It will be noted that in Fig. 1 the rollers 51 are formed with spaced circular disks 52 which engage the sides of the journal. On the other hand in Fig. 8 a spiral rib 53 is provided to engage the journal, the configuration of the spiral serving to carry the lubricant from one end of the journal to the other.

In Fig. 9 the rib 54 is likewise spiral but is formed with a greater pitch, and furthermore a pair of such ribs may be employed as shown in said figure to carry the lubricant back and forth more quickly. It is to be understood that either of these rollers may be employed in my invention, and furthermore that the parts of the device may be formed of similar or dissimilar metals or of any kind of material found desirable and efficient for the purpose.

While I have illustrated and described my invention with some degree of particularity, I realize that in practice various alterations thereover may be made, and I therefore desire to reserve the right and privilege of changing the form of the details of construction, or otherwise altering the arrangement of the correlative parts without departing from the spirit of the invention or the scope of the appended claims.

Having thus described my invention what I claim as new and desire to secure by Letters Patent is:—

1. A railway journal lubricator including a reservoir, a frame removably supported upon the reservoir, lugs carried by the frame, a spring strip mounted on each lug, and a pair of lubricating rollers supported at their ends upon the strips.

2. A railway journal lubricator including a reservoir, a frame mounted upon the reservoir, lugs formed interiorly of the frame, spring strips mounted on the lugs, the ends of the strips being curved upward, and a pair of lubricating rollers located within the frame to extend into the reservoir, the ends of the rollers being seated within and supported upon the curved ends of the spring strips to resiliently hold the rollers against the railway journal.

3. A railway journal lubricator including a reservoir, a frame removably mounted upon the reservoir, means within the reser-

voir for supplying lubricant to the railway journal, and a pair of shields mounted on the frame to extend upward at opposite sides of the journal to direct lubricant back into the reservoir.

4. A railway journal lubricator including a reservoir, a frame removably mounted upon the reservoir, means mounted within the frame for applying lubricant to the railway journal, a strip extending longitudinally adjacent each longitudinal edge of the frame in spaced relation to said sides of the frame, a pair of shields, one being mounted on each longitudinal side of the frame to extend upward at each side of the journal to receive lubricant and direct the same downward whereby the lubricant is guided by the strips back into the reservoir.

5. In combination with a railway journal and journal box, of a journal lubricator including a reservoir, a pair of longitudinally extending spaced ribs formed on the under side of the reservoir, spaced ribs extending transversely of the reservoir and connecting the ends of the longitudinal ribs to form a recess, and a curved resilient member having one end bent to form an edge to be inserted in the recess, the other end of the spring member engaging the under side of the reservoir, and the intermediate portion of the member engaging the journal box to support the reservoir.

6. A tool for inserting a lubricator in a journal box including a pair of parallel members having recesses formed on adjacent ends and the other end connected to form a handle.

In testimony whereof I affix my signature in presence of two witnesses.

JOSÉ M. URBIETA.
